(57) **CLAIM**

The ornamental design for a LED flare, as shown and described.

DESCRIPTION

The present application is related to each of the following commonly-owned, co-pending U.S. patent applications: 1) design application No. 29/387,692, filed Mar. 16, 2011, entitled “LED Flare;” 2) No. 13/049,761, filed Mar. 16, 2011, entitled “LED Flare;” and 3) No. 13/105,994, filed Mar. 12, 2011, entitled “LED Flare;” The entirety of each of these related applications above is incorporated by reference in the present application.

FIG. 1 is a side view of a first image of a LED flare showing the design;

FIG. 2 is a side view of a second image thereof;

FIG. 3 is a top view of a third image thereof;

FIG. 4 is a bottom view of a fourth image thereof;

FIG. 5 is a perspective bottom view of a fifth image thereof;

and,

FIG. 6 is a perspective top view of a sixth image thereof.

1 Claim, 2 Drawing Sheets

FIG. 4

FIG. 1

FIG. 3

FIG. 2

FIG. 6

FIG. 5
